US0D1110818S

(12) **United States Design Patent** (10) **Patent No.:** **US D1,110,818 S**
(45) **Date of Patent:** **** Feb. 3, 2026**

(54) **PLANT STAND**

(71) Applicant: **Liqliang Liao**, Huizhou (CN)

(72) Inventor: **Liqliang Liao**, Huizhou (CN)

(**) Term: **15 Years**

(21) Appl. No.: **29/957,577**

(22) Filed: **Aug. 14, 2024**

(51) **LOC (15) Cl.** **08-01**

(52) **U.S. Cl.**

USPC **D8/1; D11/143**

(58) **Field of Classification Search**

USPC D6/403; D8/1, 14; D11/143, 152

CPC A01G 9/12; A01G 9/122; A01G 9/022;

A01G 13/27

See application file for complete search history.

(57) **CLAIM**

The ornamental design for a plant stand as shown and described.

DESCRIPTION

FIG. 1 is a perspective view of view of a plant stand showing my new design;

FIG. 2 is another perspective view thereof;

FIG. 3 is a front elevational view thereof;

FIG. 4 is a rear elevational view thereof;

FIG. 5 is a left elevational view thereof;

FIG. 6 is a right elevational view thereof;

FIG. 7 is a top plan view thereof;

FIG. 8 is a bottom plan view thereof;

FIG. 9 is a bottom-front-left perspective view thereof, wherein the plant stand is shown in another assembled configuration;

FIG. 10 is a top-front-right perspective view thereof;

FIG. 11 is a top-rear-right perspective view thereof;

FIG. 12 is a top-front-right perspective view thereof;

FIG. 13 is a bottom-rear-left perspective view thereof;

FIG. 14 is a top-rear-right perspective view thereof;

FIG. 15 is a bottom-front-left perspective view thereof; and,

FIG. 16 is a top-front-right perspective view thereof.
